UNITED STATES PATENT OFFICE.

EDWARD E. BARRETT, OF LA GRANGE, ILLINOIS.

LOADING AND UNLOADING APPARATUS.

990,952.

Specification of Letters Patent.

Patented May 2, 1911.

Application filed June 10, 1909. Serial No. 501,225.

To all whom it may concern.

Be it known that I, EDWARD E. BARRETT, a citizen of the United States, residing at La Grange, in the county of Cook and State 5 of Illinois, have invented a certain new and useful Improvement in Loading and Unloading Apparatus, of which the following is a specification.

My invention relates to coal handling devices.

It is illustrated in the accompanying drawings, wherein—

Figure 1 is a front elevation; Fig. 2 a cross section showing the bucket on its upward path; Fig. 3 a cross section showing the bucket at the bottom of its excursion; Fig. 4 is a detail of the operating bar.

Like parts are indicated by the same letters in all the figures.

20 A A are buckets adapted to move vertically, provided each with a hoisting rope A¹ secured to the strap A² which is riveted on the bucket. The buckets on their sides are preferably provided with flanges A³ A³, 25 between which they receive the vertical guide bars A⁴, whereby the buckets are held to a fixed path of travel.

A⁵ is a pocket into which the bucket is received, A⁶ a rim therefor and A⁷ an angle bar flange about the bucket which engages the rim when the bucket has reached the lower limit of its downward excursion.

B is a supply hopper with inclined bottoms as shown and suitably supported on 35 any framework and foundation, parts of which are indicated by the letters B¹ B¹. B² is an opening in the bottom of said hopper beyond which extends the inclined floor B³. This floor is preferably made in sections or provided with an extension B⁴ also inclined but at a lower level than the floor B³. The two together form a fixed gravity chute for the discharge of the coal from the hopper. I call this chute when arranged 45 as here shown, an interrupted chute. The lower end of this chute is provided with a discharge end B⁵ hinged at B⁶ and normally held in an elevated position by means of a rope B⁷ which is connected to the discharge end at B⁸ and passes over the pulley B⁹ and has secured to its other end the balancing weight B¹⁰. The weight of the coal overcomes the gravity of the weight B¹⁰ and throws the discharge end in the position

shown in Fig. 3, but when there is no coal flowing through the inclined chute the discharge end is folded up as indicated in Fig. 2.

C is an operating bar each end of which is provided with a double link C¹ which carries 60 each two grooved rollers C² C², one above and one below the bar. These rollers are adapted to engage, by receiving into their grooves, the vertical guide rails C³ C³. To the upper end of each link C¹, is secured an operating rope D. This rope passes upwardly over a pulley D¹ and then downwardly about a narrow drum D² on the end of the measuring gate to which it is secured at the point D³. When the bucket descends, 70 its projecting flange A⁷ engages the bar C and forces it downwardly thus drawing upon the ropes D D and turning the measuring gate around, until as indicated in Fig. 3, it has cut off the supply of coal on the 75 hopper side and discharged the load of coal in the measuring gate into the inclined chute, whence it passes into the bucket in the bottom of the pocket.

Attached to each of the drums at the 80 point E is a rope E¹ which passes along the pulley E² thence upwardly and along the pulley E³, thence across to the adjacent hoist over a pulley E⁴, thence down along the pulley E⁵ and thence to a similar point of 85 attachment on the drum of the measuring gate associated with said adjacent hoist. In like manner another rope F is attached in a similar position on the drum whence it passes over the pulley F¹ the pulley F², 90 thence across to the other hoist where it passes over the pulley F³ and thence down over the pulley F⁴ and thence to a similar point of attachment on the drum of the measuring gate associated with that hoisting 95 shaft.

Assuming now, that when the bucket in one shaft is in the position shown in Fig. 2 with its measuring gate loaded and ready to be operated and that the bucket thereupon 100 descends to the position shown in Fig. 3 thereby as previously described, rotating this measuring gate until the gate has assumed the position of Fig. 3, it will be clear that this rotation of the gate, which is in a 105 counter clockwise direction, winds up the ropes E¹ and F with the result that the gate in the opposite shaft is rotated in the

- opposite direction from the gate shown in Fig. 3. In other words, when the bucket in one shaft descends, it rotates its associated gate in a given direction to cause it to discharge and by the same action it rotates the gate in the other shaft in the opposite sense so as to bring it into position of loading. The two drums are therefore at a given moment in the position shown in Figs. 2 and 3, one loaded and acting as a gate, the other empty and acting as a gate. This condition is reversed by the downward movement of the bucket, which simultaneously moves both gates in the manner suggested.
15. G is a shaft mounted on the bearings G¹ G¹ on the frame pieces provided with spokes G² G², end pieces G³ G³ and a peripheral plate G⁴ which incloses about one-half of this cylindrical measuring gate, the other half is open.
16. J is the upper part and J¹ the sides of the case in which the measuring gate is mounted, the lower part of such case being formed about the fixed inclined chute.
20. I do not wish to be limited to the precise form, arrangement, relation and location of these several parts, as of course, they can be greatly altered without departing from the spirit of my invention.
25. I shall point out in my claims the essential features. I may say here that the best exemplification of my invention would be an apparatus in which there are two vertically moving buckets, two rotatable measuring gates interposed between the hopper and the bucket shafts, two inclined chutes from the hopper to the bucket consisting of two separate fixed inclined chutes and a movable discharge end, the rotatable measuring gate interrupting such inclined chutes or separating two of its sections, means whereby the two measuring gates are simultaneously operated in opposite senses and means whereby the motion of the bucket operates the gates.
30. The use and operation of my invention will be sufficiently evident from what has already been said. When a given bucket descends it finds the measuring gate of its shaft loaded and in the position indicated in Fig. 2 because that gate has been brought to that position by the action of the other bucket in the other shaft. When the bucket question descends, it strikes the operating bar and rotates its associated gate so as to receive its supply of coal from such measuring gate but by the same action and through the ropes, it transmits power to the other measuring gate, moves it in the opposite sense, turns it so that its open side is toward the hopper and its peripheral plate toward the shaft whereupon such other gate fills and remains in the position shown in Fig. 2. When the operating bucket rises, the discharge end rises and thus the opera-

tion continues, each descending bucket alternately loading and setting the measuring gate for the other.

It will be understood of course that the measuring gates are proportioned so as to supply the desired amount of coal to the bucket. It will be observed that the peripheral plate acts all the time as a gate and that it is first on the hopper side and then on the shaft side. It will also be observed that this plate operates as a chute to a certain extent discharging the coal from within the measuring gate down over the plate even to the last moment of its motion as shown in Fig. 3. Thus the coal forces down along the inclined bottom or the upper part of the fixed chute B³ into the gate or in other words into the peripheral plate which operates in a sense as a continuation of the chute B³. When the action of the bucket is reversed the peripheral plate acts as a discharge chute gradually discharging the coal over its surface and finally over its lower end, thus interrupting and bridging the space between the two fixed chutes B³ and B⁴.

I have described my device as applicable to the handling of coal but of course it is suitable for any flowing solid. I have also described and illustrated my improvements in connection with the two buckets and two shaft structures but obviously many important features of my invention are fully utilized in a single bucket apparatus. The particular means of communicating motion from the bucket to the measuring gate is here shown as suitable for a two shaft and double bucket structure.

I claim:

1. In a loading and unloading apparatus, the combination of a hoisting bucket moving in a definite path with a fixed supply hopper at one side of such path, a two part inclined fixed chute leading from the hopper to the shaft and intermediate the two parts of the chute, a pivotally mounted combined gate, measure and chute through which the material intermittently flows in measured quantities from the hopper to the bucket.

2. In a loading and unloading apparatus, the combination of a hoisting bucket moving in a definite path with a fixed supply hopper at one side of such path, an inclined fixed chute leading from the hopper to the shaft and intermediate the ends of the chute, a pivotally mounted combined gate, measure and chute through which the material intermittently flows in measured quantities from the hopper to the bucket.

3. In a loading and unloading apparatus, the combination of a hoisting bucket moving in a definite path with a fixed supply hopper at one side of such path, a two part inclined fixed chute leading from the hopper to the shaft and intermediate the two parts

of the chute, a pivotally mounted cylindrical combined gate, measure and chute through which the material intermittently flows in measured quantities from the hopper to the bucket.

4. In a loading and unloading apparatus, the combination of a hoisting bucket moving in a definite path with a fixed supply hopper at one side of such path, an inclined fixed chute leading from the hopper to the shaft and intermediate the ends of the chute, a pivotally mounted cylindrical combined gate, measure and chute through which the material intermittently flows in measured quantities from the hopper to the bucket.

5. In a loading and unloading apparatus, the combination of a hoisting bucket moving in a definite path with a fixed supply hopper at one side of such path, a two part inclined fixed chute leading from the hopper to the shaft and intermediate the two parts of the chute, a pivotally mounted combined gate, measure and chute through which the material intermittently flows in measured quantities from the hopper to the bucket and a movable discharge end on the inclined chute with means for normally folding it up out of the path of the bucket.

6. In a loading and unloading apparatus, the combination of a hoisting bucket moving in a definite path with a fixed supply hopper at one side of such path, an inclined fixed chute leading from the hopper to the shaft and intermediate the ends of the chute, a pivotally mounted combined gate, measure and chute through which the material intermittently flows in measured quantities from the hopper to the bucket, and a movable discharge end on the inclined chute with means for normally folding it up out of the path of the bucket.

7. In a loading and unloading apparatus, the combination of a hoisting bucket moving in a definite path with a fixed supply hopper at one side of such path, a two part inclined fixed chute leading from the hopper to the shaft and intermediate the two parts of the chute, a pivotally mounted cylindrical combined gate, measure and chute through which the material intermittently flows in measured quantities from the hopper to the bucket and a movable discharge end on the inclined chute with means for normally folding it up out of the path of the bucket.

8. In a loading and unloading apparatus, the combination of a hoisting bucket moving in a definite path with a fixed supply hopper at one side of such path, an inclined fixed chute leading from the hopper to the shaft and intermediate the ends of the chute, a pivotally mounted cylindrical combined gate, measure and chute through which the material intermittently flows in measured quantities from the hopper to the bucket and a movable discharge end on the in-

clined chute with means for normally folding it up out of the path of the bucket.

9. In a loading and unloading apparatus, the combination of a hoisting bucket moving in a definite path with a fixed supply hopper at one side of such path, a two part inclined fixed chute leading from the hopper to the shaft and intermediate the two parts of the chute, a pivotally mounted combined gate, measure and chute through which the material intermittently flows in measured quantities from the hopper to the bucket and means for rotating the combined gate, measure and chute responsive to the movement of the bucket.

10. In a loading and unloading apparatus, the combination of a hoisting bucket moving in a definite path with a fixed supply hopper at one side of such path, an inclined fixed chute leading from the hopper to the shaft and intermediate the ends of the chute, a pivotally mounted combined gate, measure and chute through which the material intermittently flows in measured quantities from the hopper to the bucket, and means for rotating the combined gate, measure and chute responsive to the movement of the bucket.

11. In a loading and unloading apparatus, the combination of a hoisting bucket moving in a definite path with a fixed supply hopper at one side of such path, a two part inclined fixed chute leading from the hopper to the shaft and intermediate the two parts of the chute, a pivotally mounted cylindrical combined gate, measure and chute through which the material intermittently flows in measured quantities from the hopper to the bucket and means for rotating the combined gate, measure and chute responsive to the movement of the bucket.

12. In a loading and unloading apparatus, the combination of a hoisting bucket moving in a definite path with a fixed supply hopper at one side of such path, an inclined fixed chute leading from the hopper to the shaft and intermediate the ends of the chute, a pivotally mounted cylindrical combined gate, measure and chute through which the material intermittently flows in measured quantities from the hopper to the bucket and means for rotating the combined gate, measure and chute responsive to the movement of the bucket.

13. In a loading and unloading apparatus, the combination of a hoisting bucket moving in a definite path with a fixed supply hopper at one side of such path, an inclined fixed chute leading from the hopper to the shaft and intermediate the ends of the chute, a pivotally mounted combined gate, measure and chute through which the material intermittently flows in measured quantities from the hopper to the bucket, an operating bar in the path of the bucket and a connection

4
therefrom to the combined gate, measure and chute whereby the latter is moved responsive to the motion of the bucket.

14. In a loading and unloading apparatus, the combination of two hoisting buckets moving each in a definite path with a fixed supply hopper at one side of such path, inclined fixed chutes leading from the hopper to the shafts and intermediate the two ends of each chute, a pivotally mounted combined gate, measure and chute through which the material intermittently flows in measured quantities from the hopper to each bucket and means for operating such pivotally mounted devices so that they simultaneously operate in opposite senses.

15. In a loading and unloading apparatus, the combination of two hoisting buckets moving each in a definite path with a fixed supply hopper at one side of such path, inclined fixed chutes leading from the hopper to the shafts and intermediate the ends of each chute and each hopper and its respective path a pivotally mounted combined gate, measure and chute through which the material intermittently flows in measured quantities from the hopper to each bucket and means for operating such pivotally mounted devices so that they simultaneously operate in opposite senses said means associated with the bucket so that each bucket alternately operates both of such pivoted devices.

16. In a loading and unloading apparatus the combination of a hoisting bucket moving along fixed guides in a shaft, with a fixed supply hopper at one side of the path of said bucket, a covered chute leading from the hopper to the shaft, and having therein a pivotally mounted cylindrical combined gate, measure and chute through which the material intermittently flows in measured quantities from the hopper to the bucket.

17. In a loading and unloading apparatus, the combination of a hoisting bucket moving in a definite path with a fixed supply hopper at one side of said path, a two-part interrupted, inclined, fixed chute leading from the hopper to the shaft and intermediate the two parts of the chute, a pivotally mounted combined gate and measure through which the material intermittently flows in

measured quantities from the hopper to the bucket.

18. In a loading and unloading apparatus, the combination of a hoisting bucket moving in a definite path with a fixed supply hopper at one side of said path, an interrupted, inclined, fixed chute leading from the hopper to the shaft and intermediate the ends of the chute, a pivotally mounted combined gate and measure through which the material intermittently flows in measured quantities from the hopper to the bucket.

19. In a loading and unloading apparatus, the combination of a hoisting bucket moving in a definite path with a fixed supply hopper at one side of said path, a two part interrupted, inclined chute leading from the hopper to the shaft and intermediate the two parts of the chute, a pivotally mounted combined gate and measure through which the material intermittently flows in measured quantities from the hopper to the bucket.

20. In a loading and unloading apparatus, the combination of a hoisting bucket moving in a definite path with a fixed supply hopper at one side of said path, an interrupted, inclined chute leading from the hopper to the shaft and intermediate the ends of the chute, a pivotally mounted combined gate and measure through which the material intermittently flows in measured quantities from the hopper to the bucket.

21. A loading and unloading apparatus comprising a fixed hopper, an inclined chute leading therefrom, said chute made up of two sections, one slightly below the termination of the other, and a combined gate and measuring device at the end of the first section.

22. A loading and unloading apparatus comprising a hoisting bucket, a path therefor, a supply hopper at one side of the path and an interrupted chute leading from the hopper to the path, a cylindrical gate and measure pivotally mounted intermediate the ends of the chute.

EDWARD E. BARRETT.
